(57) **CLAIM**

The ornamental design for a toothbrush head, as shown & described.

DESCRIPTION

FIG. 1 shows the perspective view of a toothbrush head showing my new design;

FIG. 2 shows top view of FIG. 1 thereof, enlarged for clarity;

FIG. 3 shows front view of FIG. 1 thereof, enlarged for clarity;

FIG. 4 shows side view of FIG. 1 thereof; and,

FIG. 5 shows the enlarged view of the head from FIG. 1. The broken lines in the drawings depict portions of a toothbrush head that form no part of the claimed design.
